ROOFING

Filed Jan. 30, 1928

By Inventor
Albert E. F. Moone
Wilson, Mann & Cox, Attys.

UNITED STATES PATENT OFFICE

ALBERT E. F. MOONE, OF CHICAGO, ILLINOIS, ASSIGNOR TO THE LEHON COMPANY, A CORPORATION OF ILLINOIS

ROOFING

Application filed January 30, 1928. Serial No. 250,404.

The invention relates to what is known in the trade as prepared roofing which usually consists of a foundation sheet of fibrous character commonly called felt, which sheet 5 is impregnated with a waterproof composition and, in many instances, has applied to one side a coating of adhesive asphalt in which a layer of grit is embedded.

This material is so flexible that very little 10 force is required to bend it. Consequently, when laid upon a roof in overlapping courses the weather portions are likely to be lifted by the elements, permitting rain, snow, or the like, to enter between the 15 courses and hence through the roof.

The principal object of this invention is to provide a fastening means and a method of laying that will permit the weather portions to be effectively and economically 20 cured. The preferred embodiment of the invention is illustrated in the accompanying drawings, in which

Fig. 1 is a plan view of a portion of a roof;

Fig. 2 is a section taken on the line 2—2 of Fig. 1, and

Fig. 3 is a perspective view of a portion of a roofing element equipped with fasteners of the preferred form.

However, this specific illustration and the correspondingly specific description are intended as illustrative only, for I realize that other forms may be readily devised without departing from the spirit of the invention and, therefore, the scope of the patent is to be found in the appended claims.

The supporting structure 10, shown best in Fig. 2, may be a roof or a wall, and upon this is a covering formed of a plurality of 40 overlapping courses of prepared roofing.

In this preferred form each strip or sheet includes a body portion 11 and a plurality of tabs 12 of semi-hexagonal form separated by complemental spaces 13. On the lower 45 side of each tab there is secured a fastener, generally indicated at 14. It is made of thin bendable sheet metal and comprises a base 15 and a tongue 16, the latter projecting beyond the end of the tab. The base is 50 cut on the lines 17 and 18 to form spurs, or

rivets, which may be inserted through the roofing and clinched on the opposite side.

In laying the roof the first course 19 is made of a plain sheet of prepared roofing nailed to the supporting structure at 20. 55

In laying the next course a strip or sheet like that illustrated in Fig. 3 is placed upside down beyond the eave and the tongues 16 inserted beneath the first course 19. The strip is then revolved about the eave upwardly to take its proper position top side up with the tabs flush with the eave. During this revolution the tongues 16 are bent somewhat short around the lower edge of the first course and the blow of a hammer on 60 each fastener serves to embed the fastener in the roofing material and secure each tab firmly to the first course. 65

In the second course a similar operation is performed, the strip being laid upside down with its tabs in the spaces between the tabs of the second course and the tongues 16 under the body portion of the second course. Next, it is revolved to take its proper position with the ends of the tabs 70 coinciding with the upper edges of the recesses of the course below and its body portion lying against the supporting structure where it is nailed. This operation is continued until the covering is completed, when 75 a suitable comb, or ridge cap is applied. 80

By reason of the relatively short bends around the edges of the roofing in the course below each tab is securely fastened down without the necessity of using nails, or the like. 85

The fasteners are easily produced by automatic machinery and applied to the tabs at the roofing factory. They lie flat and lend themselves to convenient packing and 90 shipping.

I claim as my invention:

1. Flexible prepared roofing comprising a body portion, a plurality of tabs on one side of the body portion spaced by recesses 95 of complemental shape and a thin bendable metal fastener secured to the underside of each tab, and projecting beyond the tab whereby such roofing is adapted to be laid in overlapping courses with the tabs of each 100

course staggered with the tabs of the course below, each course being first placed upside down below the last course with the fasteners inserted freely beneath the body of said last laid course and the respective tabs in the corresponding recesses and then rotated about the ends of the tabs to bend the fasteners short about the edge of the body portion of the last laid course and 10 press the course being laid into overlapping relation with the course last laid.

2. A roofing strip comprising a body portion, spaced tabs thereon and a thin flat bendable metal fastener secured to the underside of each tab, and projecting beyond and in the plane of the bottom of the tab, said strips being adapted to be laid in overlapping courses with the tabs of each course staggered with the tabs of the next adjacent 15 courses and the fasteners adapted to be freely inserted upwardly beneath the body portion of the course below and to be bent by the strip about the lower edge of the body portion when the strip is rotated upwardly 20 into overlapping relation with the course last laid.

3. A roofing strip comprising a body portion, and a plurality of thin bendable metal fasteners secured to the underside of the 30 body along one edge thereof, and projecting beyond and in the plane of the bottom of the strip, said strips being adapted to be laid in overlapping courses with the fasteners adapted to be freely inserted upwardly 35 beneath the body portion of the course below and to be bent by the strip about the lower edge of the body portion when the strip is rotated upwardly into overlapping relation with the course last laid.

40 In testimony whereof I affix my signature.
ALBERT E. F. MOONE.
